CLAIM

The ornamental design for a medical device connector, as shown and described.

DESCRIPTION

FIG. 1 is a top view of a medical device connector incorporating my design;

FIG. 2 is a front elevation of the medical device connector;

FIG. 3 is a bottom view of the medical device connector;

FIG. 4 is a right-side elevation of the medical device connector;

FIG. 5 is a left-side elevation of the medical device connector; and,

FIG. 6 is a perspective view of the medical device connector. The broken lines depicting the flexible tube and the interior structure of the fittings illustrate those portions of the article which are environment. The “S-break” broken lines indicate that the medical tubing shown is of no particular length. None of the broken lines form part of the claimed design.
